UNITED STATES PATENT OFFICE.

WILLIAM C. HERRICK, OF WAPELLO, IOWA.

REFRIGERATOR.

SPECIFICATION forming part of Letters Patent No. 625,301, dated May 16, 1899.

Application filed September 1, 1898. Serial No. 690,021. (No model.)

To all whom it may concern:

Be it known that I, WILLIAM C. HERRICK, a citizen of the United States, residing at Wapello, in the county of Louisa and State of 5 Iowa, have invented a certain new and useful Improvement in Refrigerators, of which the following is a specification.

My invention relates to improvements in refrigerators, and has for one of its objects 10 to provide a refrigerator in which the space in its interior may be utilized to the best advantage for storing articles of different sizes and in which cold may be radiated from all parts of the ice, and hence the ice be utilized 15 to its maximum capacity in cooling the interior of the refrigerator.

Another object of my invention is to provide a refrigerator in which a perfect circulation of air is had through all parts of its 20 interior, the accumulation of moisture at the top of the interior prevented, and the drip from the ice be kept away from the sides of the refrigerator and conveyed into a pan below the ice.

25 Another object of my invention is to provide an improved vertically-adjustable rack to receive the ice, whereby the size of the ice-chamber may be made to correspond with the quantity of ice it is to contain, so that the 30 storage-space within the refrigerator not used for ice may receive other articles to be cooled.

Another object of my invention is to provide improved means for collecting the drip from the ice, for storing it within the refrigerator to be drawn off for drinking purposes, &c., and in this connection to provide a drip-pan adapted to fit under the ice-rack and be 35 vertically adjustable therewith and which may be readily and easily detached and removed from the refrigerator to be cleaned and which is also designed to receive a filtering material, through which all the drip from the ice must pass before entering the water-tank.

40 These objects I accomplish in the manner and by the means hereinafter more fully described in detail and particularly pointed out in the claims, reference being had to the accompanying drawings, in which like figures 45 represent like parts in all the views.

Figure 1 is a front elevation of a refrigerator with my invention, partly broken away

to show the interior. Fig. 2 is a longitudinal sectional view of same. Fig. 3 is a transverse sectional view of same. Fig. 4 is a detail view of bed for ice-rack and drip-pan. Fig. 5 is a detail view of the ice-pan. Fig. 6 is a cross-sectional view of the frame and ice-pan with rack in place.

Referring to the accompanying drawings, 55 1 is the frame of a refrigerator, preferably double-walled and provided with suitable doors 2, located in the refrigerator shown in the drawings in front, but which may be located at the sides or top, as desired. A trans- 60 verse vertical partition 3 divides the interior of the refrigerator into two compartments. Said partition 3 extends from a short distance above the floor of the refrigerator to within a short distance of the roof, the top of said 65 partition 3 being inclined at an angle over and to about the center of the compartment of the refrigerator in which the ice is placed. The openings at the top and bottom of said partition 3 permit the free circulation of air 70 from one compartment to the other. Notched uprights 4 are fixed opposite each other in one of said compartments, so that the notches on one face the notches on another. Shelves 75 5, preferably slatted, rest on said notches and 75 may be adjusted by means of said notches at any desired distance apart, so as to receive articles of different sizes. In the remaining compartment similar notched uprights 6 are 80 similarly placed, and also at the sides of this 85 compartment, as well as the inner surface of the door 2, which enters this compartment, a series of vertical flat strips 7 are placed, reaching to within a short distance of the top, and across these strips 7 at suitable intervals 90 guards 8 are placed. Said guards 8 project sufficiently far out to reach over the edges of the ice-pan 9 and have at their outer edges downward-projecting flanges 10 and serve the double purpose of keeping the ice from coming 95 in contact with the walls of the refrigerator and to carry the water from the ice into the pan 9. The sides of said pan 9 are higher than the ends, and when the pan 9 goes in the side guards 8 act as grooves to hold the pan 9 firmly 100 in place, while the ends of the pan 9 pass under the front and rear guards 8, which do not come down and over clamp-like as the side guards 8 do. A rectangular frame 11, open

in the center, the top of said frame 11 inclined downward toward said opening and the bottom of said frame 11, on each side of said opening, provided with slides 12, adapted 5 to receive the edges of the drip-pan 13, rests on the notches of said uprights 6 and is adapted to be adjusted vertically. The ice-pan 9 consists of a rim 14, adapted to rest on the frame 11, said rim 14 having its sides higher than 10 its ends and its bottom pieces extending inwardly and downwardly, so that the water from the ice supported within this rim 14 will be conducted to the opening in the center of the rim 14. Flat metal bars 15 rest within 15 said rim 14 and have a series of V-shaped metal bars 16 fixed thereto, forming a grate upon which the ice rests. A drip-pan 13 has flanges 18, extending outwardly from the top of its sides and adapted to engage the slides 20 12 and a bottom inclined downwardly and toward the center at the back, where it terminates in a spout 19. In the drip-pan 13 filtering material 20, preferably brick-clay, tile, or porous stone, is placed sufficient to 25 approximately fill said pan 13. At the rear of this compartment of the refrigerator is placed a U-shaped chute 21, terminating in a round spout 22. This chute 21 is designed to receive the rear end of spout 19, and hence 30 all of the water passing through the drip-pan 13 will be conveyed through this chute 21. A tank 23, here shown L-shaped, fitting in a recess in the walls and closed on the top and sides, is placed in the bottom of this compartment 35 of the refrigerator. An opening 24 is formed in the top of the tank 23 directly under the spout 22 and a pipe 25 leads from the opening 24 to a point near the bottom of the tank 23, so that the cold water may pass directly 40 to the bottom of the tank 23. A faucet 26 passes through the wall of the refrigerator and is screwed into the tank 23 a little below the level of the bottom of the pipe 25 to permit water to be drawn from the tank 23. Near 45 the top of the tank 23 is an overflow-pipe 27, arranged so that the warmest water in the tank 23 will drip into the pan in the bottom of this compartment of the refrigerator when the tank 23 becomes too full.

50 It is obvious that the ice-pan 9 may be placed at any height that is necessary to permit the desired quantity of ice to be placed above it, leaving all the rest of the space for other articles; that a free circulation of air is had from the bottom of the ice downwardly 55 for the reason that there is a considerable space between the bottom of the grate on which the ice rests and the top of the drip-pan 13 and because the drip-pan 13 is much smaller than the interior of the compartment, so that the cold from the ice may radiate downwardly and outwardly around the drip-pan 13; that all of the drip from the ice will be conveyed to a tank 23, from which it may 60 be drawn off for drinking purposes, and this water is thus collected and drawn off no matter at what point of elevation the ice-pan 9 may

be and also without stopping or interfering in any way with the circulation of air from the bottom of the chamber; that a free circulation of air around the side of the ice-chamber is provided at all times by means of the flatstrips 7, which surround the ice-chamber and provide a series of flues around the ice-chamber, which flues, as hereinbefore 70 stated, extend only to a point near the top of the refrigerator, and hence the air-currents passing through the flues will not strike the top of the refrigerator, but will be diffused and spread out, thus preventing the deposit 75 of a quantity of moisture on the top, as would be the case if the currents of moisture-laden air struck directly against the top; that the drip-pan 13 may be readily and quickly detached at any time and the filter therein 80 easily and conveniently cleaned; that the tank 23 for containing the filtered water by being located, as shown in the drawings, in a recess 85 in the walls of the refrigerator is made to occupy a minimum of the available space 90 within the refrigerator, (any form of tank 23, however, may be used, it being necessary only that it have an opening registering with the spout 22,) and that the openings at the top and bottom of the partition 3 will provide 95 for a free circulation of air through both compartments of the refrigerator, the inclined top of said partition 2 tending to convey the warm air directly over the ice, and hence the refrigerator will be maintained at 100 the same temperature throughout its interior.

I have described a tank in connection with my refrigerator, but the same forms no part of my invention and may be omitted at pleasure.

Having thus described my invention, what I claim as new, and desire to secure by Letters Patent, is—

1. In a refrigerator, a compartment designed to contain ice, an ice-supporting rack 110 within said compartment, means for vertically adjusting said ice-supporting rack, a drip-pan connected with said ice-supporting rack and provided with a spout, and an open chute vertically fixed to the back of the interior of said compartment and adapted to receive said spout and to convey the drip-water 115 from the pan to a point of discharge, substantially as shown and described.

2. In a refrigerator, the combination of a 120 compartment designed to contain ice, and having notched uprights at its corners, a rectangular frame adjustably supported on said notched uprights, a rim of a size to approximately fill the interior of the ice-chamber, and 125 having its bottom edges inclined downwardly and inwardly designed to rest upon the said frame, an ice-supporting rack or grate within said rim, slides fixed to the said frame and projecting downwardly therefrom, a drip-pan 130 supported in said slides at some distance beneath the ice-supporting rack, a spout at one side of said drip-pan, and a chute or gutter fixed to the interior of the refrigerator, to re-

ceive said spout and to convey the drip-water to a point of discharge, substantially as shown and described.

3. In a refrigerator, the combination of a compartment designed to contain ice, and having notched uprights at its corners, a rectangular frame adjustably supported on said notched uprights, a rim of a size to approximately fill the interior of the ice-chamber, and having its bottom edges inclined downwardly and inwardly designed to rest upon the said frame, an ice-supporting rack or grate within said rim, slides fixed to the said frame and projecting downwardly therefrom, a drip-pan supported in said slides at some distance beneath the ice-supporting rack, a filtering material contained within the drip-pan, and a chute or gutter fixed to the interior of the refrigerator to receive said spout and to convey the drip-water to a point of discharge, substantially as shown and described.

4. In a refrigerator, an ice-chamber, an ice-supporting rack in said chamber, flat strips fixed vertically on the walls of said chamber, said strips beginning at a distance from the floor of said chamber and ending at a distance from the top of the same, and guards secured at intervals across said strips, said guards ex-

tending outwardly and provided at their outer edges with downwardly-projecting flanges 30 and said strips and guards forming flues for the circulation of air, substantially as shown and described.

5. In a refrigerator, a central transverse partition reaching neither to the floor nor roof 35 of said refrigerator, said partition toward the top inclined at an angle toward the end of the refrigerator, a series of flat strips fixed vertically to the walls of the compartment over which the top of said partition projects, 40 guards secured at intervals across said strips, said guards projecting outward and provided at their outer edges with downwardly-extending flanges, an ice-supporting rack adapted to slide in under said side guards, leaving 45 space for the circulation of air between said strips and around said ice-rack and a series of adjustable open racks in the other compartment, substantially as shown and described.

In testimony whereof I hereto affix my signature in the presence of two witnesses.
